Patented Oct. 7, 1924.

UNITED STATES PATENT OFFICE.

JACOB NEMO, OF NEW YORK, N. Y., ASSIGNOR TO ANDREW NEMO, OF BROOKLYN,
NEW YORK.

VENDING MACHINE.

Application filed April 8, 1921. Serial No. 459,519.

To all whom it may concern:

Be it known that I, JACOB NEMO, a citizen of Ukrainia, and a resident of the city of New York, borough of Manhattan, in the county and State of New York, have invented a new and Improved Vending Machine, of which the following is a full, clear, and exact description.

This invention relates to vending machines and has for an object to provide an improved simplified construction which will readily operate for vending articles in bulk or individual packages.

Another object of the invention is to provide a vending machine arranged with means for detecting coins or slugs made of magnetic material and causing said coins or slugs to be deflected so as not to operate the machine.

A further object of the invention is to provide a machine in which a pivotally mounted magnet acts as a guide or chute for the coin.

In the accompanying drawings—

Figure 1 is a perspective view of a complete machine disclosing an embodiment of the invention, the same being shown in condition for operation.

Figure 2 is a vertical section through a machine similar to that shown in Figure 1, the upper part being broken away.

Figure 3 is a section through Figure 2 approximately on line 3—3.

Figure 4 is a sectional view through Figure 3 approximately on line 4—4.

Figure 5 is a side view of the operating mechanism looking at the same from the side opposite the coin wheel.

Figure 6 is a top plan view of the operating mechanism shown in Figure 3.

Referring to the accompanying drawings by numeral, 1 indicates a casing which may be made of metal or of any desired material, said casing being provided with a top plate 2 having an aperture 3 through which the articles 4 will pass. The container 5 of glass or other material is clamped in any suitable manner to the top of casing 1 so that the contents thereof may freely flow through the opening 3. In the drawing, a globe has been shown but it will be evident that other forms of container may be used without departing from the spirit of the invention. Arranged beneath the opening 3 is a bucket wheel 6 having a number of compartments or buck-

ets 7 adapted to receive articles as the buckets pass the opening 3 and later discharge 55 said articles onto the inclined chute 8 which guides under the action of gravity the articles to a dispensing cup 9 positioned exteriorly of the casing 1 so that the purchaser 60 may readily receive the articles discharged. 65

The device is particularly adapted to vend peanuts and other loose articles, though almost any article might be vended. A protecting wall 10 surrounds part of the wheel 6 while a guard wall 11 extends in front of 65 the bucket wheel so that the articles will not be dispensed before the proper time. The wheel 6 is rigidly secured by a pin 12 or other securing means to a shaft 13 rotatably mounted in the side walls 14 and 15 of the 70 chute 8. Externally of wall 14 a star wheel 16 is rigidly secured in any desired manner to the shaft 13 and is held against accidental movement by friction lever 17 pivotally mounted at 18 and urged in such a direction 75 as to press against the wheel 16 by spring 19. The arrangement is such that lever 17 will engage two of the teeth 20 of wheel 16 whereby said wheel, shaft 13 and drum 6 80 will be yieldingly locked in different positions.

In order to move the drum 6 so that one bucket at a time will move beneath the opening 3 and also one bucket at a time will discharge under the chute 8, a coin control 85 mechanism is associated with the shaft 13. This construction includes a coin arm 21 loosely mounted on shaft 13, said coin arm having a sleeve 22 extending therefrom and provided with a projection 23 to which a 90 spring 24 is connected. Spring 24 is connected to a stationary anchor preferably secured to part of the chute 8 so that the sleeve 22 and associated parts will be moved back automatically to their former position 95 when released. A stub shaft 25 is connected by a pin or other suitable means to sleeve 22, as shown in Figure 3, said stub shaft carrying a lever 26 arranged exteriorly of the casing 1 and positioned as shown in 100 Figure 1 so as to be readily depressed whenever desired. Suitable stops 27 and 28 are arranged on the casing 1 for limiting the swinging movement of lever 26. Co-acting with the coin arm 21 is a coin wheel 29, 105 which coin wheel is provided with a num-

ber of tangentially arranged blades 30, said wheel being hollowed out in the center and said hollowed out section merging into notches 31 in each blade whereby the arm 21 may move freely in the notches 31 without moving the wheel 29.

As shown in Figure 3, the blades 31 are connected by suitable side plates 32 and 33 so that a strong rigid construction is presented. If desired, the entire wheel 29 may be made from one piece or may be made from many pieces and properly connected together. By reason of this construction and arrangement, whenever a coin of the proper size is deposited as shown in Figure 4, the parts will operate for moving the drum 6 when the lever 26 is shifted. When the lever 26 is moved downwardly toward the stop 28, the coin arm 21 will move downwardly and engage the coin and then will move the coin and wheel 29 one step forward or until the compartment in back of partition 21 has moved past said partition and discharged its contents. By the time this occurs, the lever 26 will have moved to a position against stop 28 and the toothed wheel 16 is moved until the lever 17 has engaged the next tooth 20. In this way, one coin will cause one of the buckets 7 to discharge when the lever 26 has been properly actuated. In order that the coin may be properly directed to the proper blade 30 of wheel 29 a coin guide 34 is provided into which the coin is inserted and through which it passes to the U-shaped magnet 35, which magnet also acts as a guide or chute for the coin for directing the same to the proper blade 30. If the coin is of the proper size and proper material, it will move down to the position shown in Figure 4 but in case it is made of magnetic material, it will adhere to the magnet 35 and, consequently, will never reach the wheel 29 so that if the lever 26 is operated, said lever will merely move the coin arm 21 but it will not actuate the wheel 29. Wheel 29 is rigidly secured by a key or other suitable means to shaft 13 whereby whenever said wheel 29 is moved, the drum 6 will be moved. In case a steel washer or other article of magnetic material has been deposited on the magnet 35, the same will remain in position thereon until removed. This removal is accomplished when the lever 26 is moved down the first time after the article has engaged the magnet. As the lever 26 moves downwardly, extension 23 is moved pivotally against the action of spring 24 and moves the rod 36 in a substantially longitudinal direction. This rod is provided with a bent section 37 acting as a shoulder for normally supporting the magnet 35. When the rod 36 is moved by extension 23, the shoulder 37 will be moved from beneath the magnet 35 and, consequently, said magnet will move

down under the action of gravity so that the projection 38 and the bracket 39 will extend through the magnet and knock off the washer or other magnetic article on the magnet. It will be observed from Figure 4 that the magnet 35 is hinged or pivotally mounted at 40 so as to freely swing up and down. The lower end of the rod 36 is provided with a loop 41 which accommodates the pin 42 whereby said rod 36 is guided in its back and forth movement. The magnet 35 moves downwardly each time the lever 26 is moved downwardly to the stop 28 and then is moved back by shoulder 37 to the position shown in Figure 4 whenever lever 26 is released, said back or return movement being caused by spring 24. This spring also acts to bring lever 26, arm 21 and associated parts back to their former position.

In operation, whenever it is desired to secure some of the contents of the container 5, a coin of the proper size is inserted into the guide 34 and said coin will pass onto the magnet 35 and from thence down to the position shown in Figure 4 on one of the blades 30. Lever 26 is then depressed until it strikes the stop 28 after which it is released and automatically returns it to its former position. As the lever moves downwardly, it will rotate the sleeve 22 and coin arm 21 so that said coin arm will engage the coin and force the coin together with wheel 29 a predetermined distance which is sufficiently far to cause the wheel 29 to rotate the drum which is a distance of one bucket 7. When this has been done, lever 17 (Fig. 5) will have come into engagement with the next tooth 20 so that the wheel 29 will be held yieldingly locked against further movement in either direction while the arm 21 and lever 26 automatically returns under the action of spring 24. When the bucket 27 has discharged under chute 8 the material so discharged will move by gravity downwardly into member 9 so that it may be readily secured by the purchaser. In case the lever 26 is depressed without first having inserted a coin, said lever may be moved until it strikes the stop 28 and in turn it will move arm 21 but as there is no coin in wheel 29, said arm 21 will merely pass through one of the notches 31 and perform no useful work. When the lever 26 is released, the parts will again assume their former position. In case an iron or steel washer is inserted, it will be arrested by the magnet 35 and will not reach the wheel 29 so that when the lever 26 is depressed, arm 21 will have nothing to engage and, consequently, will not rotate wheel 29. However, when arm 21 is moved extension 23 will be moved and, consequently, rod 36 with its supporting shoulder 37 will be moved downwardly and allow the magnet 35 to move downwardly so that the projection 38 may

strike the washer and knock the same from the magnet. When the lever 26 is released, shoulder 37 will restore magnet 35 to its former position as shown in Figure 4 whereby 5 the parts are ready to receive a coin of the proper kind. In this way a spurious coin is disposed of without injury to the machine and without operating the vending buckets. Preferably, the bottom 43 of casing 1 is re- 10 movable and is arranged with suitable fastening means for normally holding the same in place.

As shown in Figure 3, the casing 1 is provided with a flange 46 on one side and a 15 flange 44 on the other side and a bottom with a groove 45 for receiving the flange 44 while on the opposite side the flange 46 contacts with the bottom 43 and with the bolt 47 of a suitable lock 48. Whenever it is desired 20 to remove the bottom, bolt 47 is withdrawn and bottom 43 moved pivotally a short distance until the lock 45 is clear of the bottom edge of the body 1 and then moved in a direction away from flange 44.

What I claim is:—

A vending machine of the class described, comprising an outer casing presenting a coin slot and a discharge slot, a shaft comprising two sections operatively mounted within said casing, a sleeve rigid with one of said sections overlapping a portion of the other section, a wheel having a plurality of slotted and tangentially extending vanes adapted to successively receive a coin rigidly mounted on said overlapped section, an arm secured to said sleeve and operating within said wheel and through said slots, said arm turning said wheel when a coin obstructs its free passage through any one of said slots, a vending drum rigid with said overlapped section adapted to be turned when said arm turns said wheel, a brake wheel having a plurality of teeth mounted on said shaft and a brake adapted to normally engage a pair of said teeth to allow said drum to turn only 45 a fraction of a revolution at a time.

JACOB NEMO.
